UNITED STATES PATENT OFFICE.

EUGENE P. WOILLARD, OF SUGDEN, FLORIDA.

GAS-PRESSURE GENERATOR.

SPECIFICATION forming part of Letters Patent No. 601,456, dated March 29, 1898.

Application filed July 16, 1897. Serial No. 644,856. (No model.)

To all whom it may concern:

Be it known that I, EUGENE P. WOILLARD, a citizen of the United States, residing at Sugden, in the county of Dade and State of Florida, have invented a certain new and useful Improvement in Gas-Pressure Generators, of which the following is a specification.

My invention relates especially to pressure-generators of the continuous-combustion type, whereby a greater amount of heat is saved and converted into a useful working pressure than has hitherto been possible.

The objects in view are to provide a simple and instantaneous internal-combustion pressure-generator where gas or oil-vapors or other like rapid combustibles are burned in the retort or combustion-chamber with the proper amount of air to form perfect combustion. The burned gases thus formed pass out of the combustion-chamber, where they unite or commingle with steam that has been generated in the coils that surround the inner walls of the combustion-chamber and pass from the combination to the mixing chamber. The steam issues from said pipes as "saturated" steam and, commingling with the burned gases, forms "superheated" steam, which is used expansively or otherwise in any desirable form of engine, whether it be a reciprocating, oscillating, rotary, or steam turbine, but preferably in the latter.

A further object of the invention is to provide an elastic motive fluid having the advantage of both gas and hot air and also steam without their disadvantages—namely, the tendency which gas and hot air have to destroy the sensitive parts of an engine and also the rapid falling off of the pressure—since by the addition of steam the expansive qualities are prolonged and act more as a lubricant than as a destroyer of the lubricating agent.

Further objects and advantages of my improvement will appear in the following description, and the novel features will be particularly pointed out in the claims.

In the drawings, Figure 1 is a vertical section of my improvement in its preferred form, showing plainly the construction thereof; Fig. 2, a side elevation in diagram, showing how my improvement is to be applied; and Fig. 3 is an enlarged view of the electric igniter.

Similar letters and numerals of reference

indicate corresponding parts in all the figures of the drawings.

1 is the combustion-chamber, having an opening or neck 2, leading into the mixing-chamber 3, both forming compartments within the interior of a proper casing A. Through the bottom of the combustion-chamber passes an induction-pipe 4 and is made to form a coil 5 and lining B for the retort or combustion-chamber, leaving an opening at the center of the coil for the injection-pipe 6 to pass through. Then this pipe 4 continues coiling around the inner walls of said chamber until it reaches the crown-sheet C, where it also lines the same by being properly coiled, leaving an aperture in the center thereof, so as to obstruct the passage 2. From thence said pipe 4, after lining all the inner walls or surfaces of the combustion-chamber, continues to make a series of flat coils 6, that are suspended within the upper portion of the chamber 1, and finally said coils end by turning up and passing through the central passage of the flat coils 6 and through the neck 2 into the lower end of the mixing-chamber 3, being held in position by a suitable bracket 7, through which it passes, and is secured by a nut 8. The bottom of the mixing-chamber 3 is made within a convex head, consisting of the crown-sheet C, in order that the water of condensation may be drained therefrom by the cock 9. The object of providing the two chambers 1 and 3 with a flared-neck tube between them is to keep the combustion-chamber 1 clear of any steam or moisture, so that only pure air is present to form perfect combustion in combination with the gas or oil-vapors. After the products of combustion have passed through the neck 2 into the mixing-chamber 3 and have commingled with the steam issuing through the nozzle 10 they then pass out through the education-pipe 11 to the motor or other suitable point.

To ignite the first charge in the combustion-chamber 1, I provide an electric igniter in the following manner: In the lower end of the injection-tip 5 are screwed the plugs 12, and through each of these plugs are inserted adjustable insulated electrodes 13 and 14, which are slightly separated at their inner ends, where a spark may be produced at the instant the contact is made at the switch

which completes the circuit through the electrodes 14, thence through a suitable electric battery through the switch, then through a suitable spark-coil to the other electrode 13, producing a spark at the inner ends of the electrodes 13 and 14, thus igniting the charge, after which the current is cut off, since from this time on the ignition will be continuous. Leading to the tip 5, from one side thereof, is a suitable flame-arrester 15, located in the pipe 16, and said pipe is made larger at this point in order to properly accommodate said arrester and not to impede the flow of air and gases therethrough.

15 From the foregoing description the operation of my improvement is as follows: Either a hand-pump may be used to start the generator or a pressure of air and oil-vapors or gases may be stored in any suitable tank or holder. 20 In the latter case upon opening the valve controlling the flow from the tank to the pipe 16 and operating at the same time the electric switch to cause a spark to take place at the inner ends of the electrodes 13 and 14 said 25 charge will be ignited and passed into the combustion-chamber 1, thus creating a pressure which will at once be indicated upon the gage D, and at the same time or any time thereafter the motor may be started, thus operating the air and vapor compressor E and also the water-pump F, which furnishes the water to generate the steam in the coils that line the combustion-chamber. The generator and motor are now considered under way 30 and the pressure tank or holder may be cut off, permitting the governor G to take care of the motor, as said governor controls both the air and vapor valves and also the water-valve; but if there be no governor these valves may 35 be controlled by hand.

40 The exhaust of the motor is used to pass through a suitable heating-drum H, in which proper coils are arranged for the heating of the water and also the air and vapors. Thus 45 it will be seen that nearly all heat generated is made to do duty and that very little is thrown away.

It will also be noticed that I provide the generator with a safety - valve I to guard 50 against accidents should the pressure pass a safe limit. The outer surface of the generator is provided with a suitable non-conducting covering or jacket J to prevent radiation or loss of heat.

55 I do not wish to be limited to the exact construction here shown, as it will be seen that various changes in the form, proportion, and the minor details of construction may be resorted to without departing from the principle or sacrificing any of the advantages of this invention.

Having thus fully described my invention, what I claim as new and useful is—

1. In combination with an internal-pressure generator having a combustion-chamber 65 1 and a mixing-chamber 3 connected by a passage 2, the combustion-chamber 1 having its bottom, sides and top lined with a steam-generating pipe 4, coiling to cover the bottom, then the sides, then the top, after which said 70 pipe 4 continues to coil and form a series of pending flat coils 6 6 6, after which said pipe 4 turns upward and passes through the opening in the center of said coils 6 6 6 up through passage 2, into the mixing-chamber 3, through 75 bracket 7, and secured in place by nut 8, substantially as described.

2. In the combination of an internal-combustion generator, a combustion-chamber 1 and a mixing-chamber 3, the combustion-chamber lined with a steam-generating pipe 4 lining the inner walls, bottom and top in coils, and a series of flat coils 6 6 6 suspended in the upper end of said combustion-chamber 1, and said pipe 4, then turns upward and 85 passes through the center of said flat coils 6 6 6 and through the passage 2 into the lower end of the mixing-chamber, an induction gas and air pipe 16, furnished with a tip 5, that passes through the bottom of the combustion-chamber 1, said tip 5 being provided with a 90 plug 12, screwed in its lower end, said plug also provided with adjustable insulated electrodes 13 and 14 passing through each side and separated from each other slightly at the 95 inner ends, substantially as described.

3. A generator of the character described, consisting of a suitable casing divided into two compartments, one serving as a combustion-chamber, and the other as a mixing-chamber, a coil of pipe arranged within the combustion-chamber for generating the steam, means for ejecting said steam within the mixing-chamber, means for supplying the combustion-chamber with combustible gases, 100 and means for igniting the same, as specified.

4. In combination a generator consisting of a casing divided into two compartments, one serving as a combustion-chamber and the other as a mixing-chamber, a coil in the combustion-chamber, a motor connected with the mixing-chamber, a pump and a compressor operated by said motor, a tank, an escape-pipe connecting said tank with the motor, and 110 pipes running from the compressor and pump through the tank to the combustion-chamber and coil respectively, substantially as set forth.

In testimony whereof I have hereunto affixed my signature in the presence of two subscribing witnesses.

EUGENE P. WOILLARD.
